UNITED STATES PATENT OFFICE

GEORGE I. MILLS, OF SPRINGFIELD, MISSOURI

WASTE RECEPTACLE

Application filed December 6, 1927. Serial No. 238,124.

This invention relates to waste baskets for general utility in homes and offices.

An object of the invention is the provision of wire holders adapted to be secured to a fixed support which will receive and clamp a piece of paper rolled into cone-shaped receptacle serving as a container for waste.

Another object of the invention is the provision of a waste basket formed of a piece of paper rolled to cone shape and supported in expanded relation by a wire holder which clamps or pinches the lower end of the cone to prevent the escape of liquid, the paper basket or container being burned or destroyed with the waste collected therein.

This invention will be best understood from a consideration of the following detailed description in connection with the accompanying drawings; nevertheless it is to be understood that the invention is not confined to the disclosure being susceptible of such changes and modifications as shall define no material departure from the salient features of the invention as expressed in the appended claim.

In the drawings:—

Figure 1 is a view in perspective of a kitchen showing my invention in operative position with a fixed support,

Figure 2 is a view in perspective of a wire holder for a paper waste basket,

Figure 3 is a view in perspective of a waste basket carried by a slightly modified form of wire holder.

Figure 4 is a view in perspective of a further form of the invention.

Referring more particularly to the drawings 10 designates generally a bracket having an attaching arm 11 which is adapted to be secured in an approved manner to a fixed support, as the side wall 12 of a closet 13. The securing means in this instance is illustrated by a pair of screw eyes 14 which receive the vertically disposed arm 11. An arm 15 extends horizontally from the upper end of the arm 11 and is bent downwardly at 16.

A holder 17 for a cone-shaped basket 18 is formed of a single piece of resilient wire. The wire is bent intermediate its ends to form a substantially circular loop 19 which is

adapted to be disposed normally in a horizontal plane. A pair of arms 20 and 21 extend downwardly from the open portion 22 of the loop and are inclined inwardly towards the vertex 23 of the cone 18 so that the arms 20 and 21 will lie in close contact with the side wall of the cone.

The free ends 24 of a pair of clamping arms 25 and 26 are flared to permit ready insertion of the lower end of the cone-shaped container or basket 18. The clamping arms 25 and 26 are bent laterally from the arms 20 and 21 respectively and are in close contact in order that they will clamp firmly the lower end of the cone as shown at 30.

In the modified form shown in Fig. 3, the arms 20 and 21 of the wire frame 31 are provided with complementary curved sections 32 and 33 to form an eye which is adapted to receive a screw (not shown) for securing the frame or holder to a fixed support.

A piece of paper is rolled into a cone-shaped container and inserted, apex downwardly, into the loop 19. At a point indicated by the numeral 30 on the cone, said cone is flattened and forced between the clamping arms 25 and 26.

When the holder and paper basket are employed in the kitchen, a newspaper may be rolled into a cone and the wire frame is made sufficiently large for the purpose. The newspaper cone when filled may be removed and burned with the contents.

Where the frame or holder is used, in a dentist's or doctor's office smaller frames and cones are employed, and the cones are formed of small sheets of white paper or any other suitable material.

In Fig. 4, a loop 40 which receives the conically shaped container is formed of a single piece of wire with the end welded at 41 and from which depends an arm 42 forming an extension of the wire forming the loop.

A pair of eyes 43 formed intermediate the ends of the arm 42 receive a vertically disposed lug 44. This lug is formed integrally with a screw 45 with the body of the screw located at substantially right angles to the lug 44.

The arm 42 has an angular extension 46

- providing a jaw which cooperates with the jaw 47 to form a clamp on the lower end of the conically shaped container. The ends of the jaws are flared as shown at 48, to facilitate the insertion of the lower end of the container. The jaw 47 extends upwardly, as shown at 49, and in parallel relation with the arm 42 and secured to the arm at a point adjacent the lower eye 43.
- 10 In this construction the cone is inserted within the loop 40 until that portion of the cone which conforms to the diameter of the loop is in contact with said loop. The lower end of the cone is then forced between the free ends 48 and clamped between the jaws 46 and 47.

I claim:—

- 20 A device of the character described comprising a circular loop, an inverted cone-shaped receptacle received by the loop and engaging said loop at points intermediate the opposite ends of the cone, a supporting member depending from the loop at a point in the circumference and lying in close association with the outer wall of the cone, a pair of clamping arms projecting from the supporting member and adapted to clamp the lower end of the cone between the arms, and means connected with the supporting member for 30 securing said supporting member to a fixed support.

Signed at Springfield in the county of Greene and State of Missouri this 13th day of October A. D., 1927.
